UNITED STATES PATENT OFFICE

2,443,174

MATERIAL HANDLING APPARATUS

Thomas K. Andersen, Staten Island, N. Y.

Application April 4, 1946, Serial No. 659,514

3 Claims. (Cl. 214—131)

1

My present invention relates to material handling equipment, such as power shovels or other loaders, and while not restricted thereto is particularly designed for use with the power shovel disclosed in the Andersen Patent No. 2,182,781, dated December 12, 1939.

The main object of my invention is to provide an improved power drive assembly including speed reduction, clutch, and brake for the hoist drum of a power shovel or other loader, by means of which the bucket or other receptacle may be positively and reliably driven and controlled at all times in its movements from loading to dumping position, and vice versa.

Other objects and advantages will appear as this description proceeds.

In the accompanying drawings wherein I have illustrated a preferred embodiment of my invention,

Fig. 1 is a side elevation of a power shovel equipped with my invention, certain parts being shown in section,

Fig. 2 is a fragmentary plan view, on an enlarged scale, of certain parts illustrated in Fig. 1, and

Fig. 3 is a side elevation of Fig. 2.

The term "bucket" as used herein is used in its broadest sense to mean any digging and/or loading implement, as a dirt bucket, snow bucket, back hoe, lifting fork, or the like, and the term "bucket arms" as used herein is likewise used in its broadest sense to mean any structure, whether a pair of arms, or a yoke, or a boom, disposed in the fore and aft line of the vehicle, by means of which the bucket is pivotally supported on the tractor or other vehicle for swinging movements in an arcuate path over the vehicle.

Referring to the drawings, I have designated generally at 10 a tractor or other vehicle on which is pivotally mounted a material holding receptacle which is actuated and controlled in its swinging arcuate movements by the instrumentalities forming the subject matter of my present invention.

The tractor is provided with the usual driving and operating motor 11, and is also provided with a roof 12 in and on which are arranged mechanisms for controlling a bucket or other receptacle or unit 13. Bucket 13 is removably mounted at the rear ends of a pair of carrying arms 14. The forward ends of arms 14 are pivotally attached to the sides of the tractor frame at 15.

Associated with the motor 11 is a power-take-

2

off shaft 16 through which power from the motor 11 is derived for operating the bucket controlling means of my present invention. Fast on the outward or free end of the take-off shaft 16 is a reduction unit comprising a bevel pinion 17 meshing with and driving a bevel gear 18 secured to the lower end of a stub shaft 19. Shafts 16 and 19 are rotatably mounted in bearings formed in a gear box 20, which encloses the pinion 17 and gear 18, as shown in Fig. 1.

Secured to the upper end of the stub shaft 19 is the lower end of a universal joint 21, the upper end of which is secured to the lower end of a vertical drive shaft 22. Shaft 22 extends vertically upward in front of the tractor, and at its upper end is connected through a universal joint 23 to the lower end of a stub shaft 24 (see Figs. 2 and 3). Stub shaft 24 is journaled in a suitable bearing in a gear box 26' mounted at the front end of the roof 12.

Fast to the upper end of stub shaft 24 within the gear box 26' is a second reduction unit comprising a bevel pinion 25 meshing with and driving a bevel gear 26, also enclosed within the gear box. Bevel gear 26 is secured to the front end of a longitudinally extending stub shaft 27 which is coupled conventionally to the driving part 28 of a clutch comprising the driving part 28 and the driven part 29.

Driven clutch part 29 is secured to the clutch shaft 30 aligned with shaft 27 and rotating when the clutch is engaged. Shaft 30 extends rearwardly through a clutch casing 31 mounted on the roof 12 in the rear of the gear casing 26'.

Secured to clutch shaft 30 rearwardly of casing 31 is a bevel pinion 32 meshing with and driving a bevel gear 33 secured to a transversely arranged sprocket shaft 34. Shaft 34 is rotatably mounted in suitable bearings in a gear box 35 formed in the roof 12 and extends outwardly at each end through the walls of the gear box. Fast on each end of shaft 34 is a sprocket 36.

Mounted in the roof 12 behind gear box 35 is a hoisting drum enclosure 43 in which is suitably mounted a drum shaft 39 arranged parallel to sprocket shaft 34 in the gear box 35. The ends of drum shaft 39 extend outwardly beyond the sides of the drum enclosure 43 and at each end thereof carry a sprocket 38, in alignment with the sprockets 36 on the shaft 34. Trained over the sprockets 36 and 38 are sprocket chains 37.

Within the drum enclosure 43 and secured to the drum shaft 39 is a cable drum 40, and on either side of, and integral with said drum is a

brake drum 44. The brake drums 44 are equipped with conventional brake bands and brake linings, but for clearness of illustration such devices have not been shown, and further and for the same reason, no showing has been made of the controlling means for said brake bands and linings.

Attached to the hoist drum 40 is one end of a hoist chain or cable 41 which passes over an idler sheave 47, rotatably mounted on a transverse shaft 48 adjacent the rear end of the roof 12, and thence extends rearwardly and downwardly and is attached at its lower end to the bucket assembly at the point 42.

Within the drum enclosure 43, in front of, adjacent to, and in alignment with the hoist drum 40, is an idler sheave 45, secured to a transversely arranged shaft 46 rotatably mounted in suitable bearings in the walls of the drum enclosure.

Suitable means (not shown) for controlling the clutch members 28 and 29, the brake bands for the brake drums 44, and for the motor 11, are arranged within convenient reach of the operator of the machine.

With the various parts constructed and arranged as above described, the operation is as follows: The motor 11 being running, the vertical shaft 22 is in rotation, and, assuming the bucket 13 to be in the position shown in Fig. 1, the operator backs the tractor into the pile of material being worked upon, until the bucket 13 is filled with such material. The operator then frees the brake bands (not shown) from the brake drums 44, operates the clutch control to bring the driving clutch element 28 into engagement with the driven clutch element 29, whereupon the shaft 30 through the intermediary of the pinion 32 and gear 33, rotates the shaft 34 carrying the sprocket chains 31 at its ends. The sprocket chains 31 passing over the sprockets 36 and 38, rotate the shaft 39 and therefore the hoist drum 40, causing the chain or cable 41 to be wound up onto the drum 40, lifting the bucket 13, with its load, upwardly and forwardly about the bucket arm pivots 15.

This upward movement of the bucket may be halted at any point by throwing out the clutch 28, 29, and tightening the brake bands (not shown) on the brake drums 44.

The operator may then move the tractor to any desired point where the load of material in bucket 13 is to be dumped. Upon reaching this point, the operator will again start the lifting operation as above described, stopping such operation at or near the point where the bucket 13 passes the vertical position. At this point the weight of the bucket assembly and the load therein will swing the bucket 13 over center toward the front of the tractor 10, whereupon the operator partially applies the brakes to the brake drums 44 to slow the descent of the bucket. The chain or cable 41 will be out of engagement with the idler sheave 47 and the bight thereof will engage with the idler sheave 45. The bucket continues to descend, with the brakes partially applied, and with the cable paying off from the hoist drum 40, until, as it reaches the desired dumping position, the operator stops it by applying full brake. In returning the empty bucket to loading position, the operation just described is reversed.

From the foregoing description, taken in connection with the accompanying drawings, it will be evident that I have provided a simple and re-

liable power drive for actuating and controlling a hoisting unit.

It will be noted that the reduction gears 17 and 18, and 25 and 26, and the sprockets 36 and 38, respectively, provide three distinct and independent reductions by means of which the high speed of the tractor motor (usually around 1400 R. P. M.) may be reduced to approximately 40 R. P. M. at the hoist drum. It is essential that the hoist drum rotate slowly, as compared with the speed of the tractor motor, in order that the available horsepower of the motor for lifting the loaded bucket may be utilized without stalling the motor and better control of the bucket be also secured.

If desired, the assembly may be provided with an automatic knock-out of known construction, whereby when the bucket passes dead center going toward either its loading or its dumping position, the clutch will be automatically disengaged, after which the operator may manually release the brake to allow the bucket to descend under control.

Likewise, if desired, the assembly may be provided with mechanism such as that shown in the application of Carle Henry, Serial No. 659,464, filed April 4, 1946, for releasing the brake without engaging the clutch, or for releasing the brake when engaging the clutch.

While I have disclosed a preferred embodiment of my invention, I recognize that the same may be variously modified to suit special installations, and accordingly assert all such modifications to be within the purview of my invention as defined in the appended claims.

Having thus described my invention, what I claim as new and desire to secure by Letters Patent is:

1. In combination with a vehicle having a roof and a motor, a bucket pivoted to the vehicle to swing vertically relative thereto over said roof, a power drive assembly for driving and controlling said bucket including a power take-off shaft to be coupled to the vehicle motor, a hoist drum shaft mounted upon the vehicle roof and extending transversely thereof, a hoist drum on said drum shaft, a hoist connection from said drum to said bucket, a cross shaft mounted upon the vehicle roof and extending transversely thereof and parallel to and in advance of said hoist drum shaft, driving connections between said cross shaft and said drum shaft, a clutch shaft mounted upon the vehicle roof and extending longitudinally thereof and in advance of said cross shaft, driving connections between said cross shaft and said clutch shaft, a clutch comprising a driving member and a cooperating driven member, said driven member being mounted on the clutch shaft, a stub shaft mounted on the vehicle roof and extending longitudinally thereof and in advance of and in alignment with said clutch shaft and operatively connected to said clutch shaft, and driving connections between said stub shaft and said power take-off shaft.

2. The combination of claim 1, and an idler shaft interposed between said drum shaft and said cross shaft and carrying an idler sheave.

3. The combination of claim 1, and a pair of brake drums on said drum shaft, one at each side of said drum, and an idler shaft interposed between said drum shaft and cross shaft and carrying an idler sheave spaced from and aligned with said hoist drum.

THOMAS K. ANDERSEN.
